UNITED STATES PATENT OFFICE.

WILMER M. WEBB, OF PHILADELPHIA, PENNSYLVANIA, ASSIGNOR TO H. T. PAISTE COMPANY, OF PHILADELPHIA, PENNSYLVANIA, A CORPORATION OF PENNSYLVANIA.

OUTLET-FIXTURE FOR CURRENT-CONDUCTORS.

1,112,953.

Specification of Letters Patent.

Patented Oct. 6, 1914.

Application filed November 14, 1911. Serial No. 660,269.

To all whom it may concern:

Be it known that I, WILMER M. WEBB, a citizen of the United States, residing in Philadelphia, Pennsylvania, have invented 5 certain Improvements in Outlet-Fixtures for Current-Conductors, of which the following is a specification.

One object of my invention is to provide an outlet conduit usually, though not necessarily, in the form of an elbow, with a removable cover, which may be applied to the casing forming the main portion of the conduit, by sliding it thereon from either of two positions; the arrangement being such 15 as to prevent the entrance of water to the fixture as well as to facilitate the drainage therefrom of such water as may enter or be formed in the same by condensation or otherwise.

20 I further desire to provide an outlet fixture in the form of a casing having two branches and an outlet opening, with a cover therefor; the casing being of such design that said cover may be applied to it 25 so as to prevent entrance of water when it is mounted with one of its branches either above or below the other or, in the case illustrated, with its short branch at the top or bottom of its long branch, the cover being of a special construction in order that 30 it may be capable of accomplishing this object.

These and other advantageous ends I secure as hereinafter set forth, reference being had to the accompanying drawings, in 35 which:

Figure 1, is a detached perspective view of an outlet fixture constructed according to my invention; and Fig. 2, is a vertical 40 section of the outlet fixture with the cover applied thereto.

In the above drawings 1 represents the main portion of my outlet fixture which is preferably in the form of an elbow having 45 two branches 2 and 3, in the present instance though not necessarily, at right angles to each other. In the preferred form of fixture one of these branches is longer than the other and is provided with an elongated opening 50 4 one end of which is directly opposite the branch 3 of the fixture. The edges of the outlet opening 4 are formed to lie in the same plane in order that there may be applied thereto a flat cover 5. This is in the 55 form of a flat elongated plate having de-

pending flanges 6 along its longitudinal sides and a depending flange 7 with an in-turned edge 8 at one of its ends; its opposite end being formed without a flange. While the longitudinal edges of the outlet 60 opening are relatively narrow and unflanged, both of the ends of said opening have outwardly projecting flanges as indicated at 9 and 10 respectively; it being noted that in the present instance I have provided a relatively 65 extended flat surface 11 between the actual end of the opening 4 and its adjacent flange 10, it being however, immaterial whether this is present or not, depending on what may be found to be the most convenient and economical form of construction.

At one end of the outlet opening 4 adjacent the flange 9, I provide a lug 12 having an opening for the reception of a screw, (although it is obvious that this screw hole 75 may be provided in the edge of the fixture without provision of a special lug if the various parts be so designed) and diametrically opposite this hole at the other end of the outlet opening 4, I provide a second 80 hole 13.

In the top or cover 5 adjacent one end thereof, I provide a hole 15 for the reception of a screw 16, and it is to be noted that the hole 14 in the lug 12 as well as the hole 13, 85 are so placed that a screw in the hole 15 of the cover will properly engage the threads of the hole 14 if said cover be placed on the outlet fixture with its flange 7 adjacent the flange 9, and will also properly engage the 90 threads of the hole 13 if the cover be so placed on the fixture as to bring its flange 7 adjacent the flange 10. In other words, it is immaterial which end of the cover is presented to the fixture, since the flange 10 as 95 well as the flange 9 is formed to fit under the inwardly turned flange 8 of said cover.

When the fixture is in use it may be employed with its outlet opening in a vertical plane and its branch 3 at its lower end, in 100 which case the cover is applied so that its flanges 7 and 8 hook onto the flange 10, or it may be in a position with the outlet opening 4 vertical and the branch 3 at the upper end thereof, when the cover flanges 7 and 8 105 would be hooked over the flange 9. Under such conditions these flanges 7 and 8 of the cover, as well as its side flanges 6 effectually prevent the entrance of rain or snow to the fixture, while the cover itself is suitably 110.

- 5 maintained in place by a screw passed through the opening 15 into either of the openings 13 or 14, depending on the relative position of the main portion of the fixture. At the same time, by reason of the fact that there is no flange at the lower end of the cover, any liquid which may enter within the body of the fixture or run down the cover is free to pass out.
- 10 10 The raised flange 17 is preferably provided around the opening 15 on the outside surface of the top or cover in order to render entrance of water around the screw 16 a practical impossibility.
- 15 15 I claim:-
1. An outlet fixture having two branches and an opening; flanges at the ends of the opening extending parallel to the plane thereof; with a reversible cover formed with 20 one end returned on itself for the reception of either flange.
  2. An outlet fixture consisting of a hollow branched structure having an opening provided with flanges at a plurality of points; 25 with a cover having a returned flange of limited extent for application to the opening of the structure in any of a plurality of positions.
  3. An outlet fixture consisting of a hollow 30 branched structure having an elongated outlet opening provided with flanges at its opposite ends; and a reversible cover having a returned flange at one end formed to fit either flange of the outlet opening.
  4. An outlet fixture consisting of a hollow 35 branched structure provided with an outlet

opening having an outwardly projecting flange; a cover having a returned flange formed to fit the flange of the outlet opening; and means for retaining the cover on 40 the branched structure.

5. The combination in an outlet fixture of a hollow branched structure having an outlet opening provided with flanges at two opposite portions and having two holes; 45 with a reversible cover having a returned flange capable of engagement with either of the flanges of said opening and having a screw capable of entering either of the holes of the branched structure to retain the cover 50 in place thereon.

6. The combination in an outlet fixture of a hollow structure having two branches at a right angle to each other and provided with an outlet opening opposite one of the 55 branches; said opening at opposite portions thereof having outwardly projecting flanges; a cover having a returned flange at one end and straight flanges along its sides adjacent said end; the returned flange being formed 60 to receive either of the flanges at the ends of the outlet opening; and means for retaining the cover in position on the branched structure.

In testimony whereof, I have signed my 65 name to this specification, in the presence of two subscribing witnesses.

WILMER M. WEBB.
